UNITED STATES PATENT OFFICE.

WILLIAM K. SPAULDING, OF KETCHIKAN, TERRITORY OF ALASKA.

SERVICE-FLAG.

1,355,861.

Specification of Letters Patent. Patented Oct. 19, 1920.

Application filed October 17, 1918. Serial No. 258,563.

To all whom it may concern:

Be it known that I, WILLIAM K. SPAULDING, a citizen of the United States, and a resident of Ketchikan, First Judicial Division, Territory of Alaska, have invented certain new and useful Improvements in Service-Flags, of which the following is a specification.

This invention relates to flags, and more particularly to a service flag, designed for indicating civilian service of a patriotic nature, such as the purchasing of Liberty bonds, subscribing to the Red Cross, Y. M. C. A. or other war activities and an object 15 of the invention is to provide a flag, as shown in my Design Patent #52,411 issued September 10, 1918, wherein the length of the flag is extensible, to permit the distributing of an increasing number of stars, as the 20 owner of the flag performs additional patriotic duties or services; and if desired, the flag could be used by societies, churches or the like in lieu of the common service flag, to indicate men in the service of the country, 25 and as the number of men from the society in either the Army or Navy increase, the flag could be unrolled to distribute a corresponding number of stars.

Other objects of the invention will appear 30 in the following detailed description, taken in connection with the accompanying drawing, forming a part of this specification, and in which drawing:

Figure 1 is a face view of the improved 35 service flag.

Fig. 2 is a fragmentary perspective view of the service flag, showing in detail the clamping structure for retaining the rolled portion of the flag in place.

Fig. 3 is a detailed section.

Referring more particularly to the drawing, 1 generically indicates the flag, which comprises a plurality of longitudinally extending alternate red and white stripes. It 15 will be noted, by particular reference to Fig. 1 of the drawing, that the stripes are arranged in such manner as to present a red stripe indicated at 2, at each edge of the flag 1, and a white stripe as indicated at 3 at 20 the center of the flag which is separated from the red stripe 2, by red stripes 4 and white stripes 5. The white stripes 5 are positioned one upon each side of the blue field 6, and the stripes 3 and 4 extend outwardly 25 from the outer end of the field 6 to the outer free end of the flag 2. The flag 2 is con-

nected to and carried by a holder structure generically indicated by the numeral 10, and this holder structure comprises a pair of members 11 and 12 which are hingedly connected, by means of a rod 13. The rod 13 extends longitudinally through hinged barrel portions indicated at 14 formed upon the upper edges of the sections 11 and 12. These sections 11 and 12 have their facing sides spaced to form a pocket as clearly shown in Fig. 3 of the drawing, in which the rolled portion of the flag 1 is positioned and their lower free edges are bent inwardly toward each other as shown at 14, for engagement upon each side of the extended portion of the flag to support the same and prevent the rolled portion from unrolling. The section 11 of the holder 10 has an 60 standing ear or tab 15 formed thereon which is provided with an opening 16 adapted to receive a nail, pin or other suitable suspending device for supporting the flag in an exhibiting position. The members 11 and 12 have longitudinally extending ears 17 65 formed upon their ends, which ears are spaced from each other and connected by means of bolts 18 and wing nuts 19. When the wing nuts 19 are tightened upon the bolts 18, the sections 11 and 12 will be 70 drawn into and held in closed position; however when it is desired to increase the length of the flag for exhibiting an increased 75 number of stars, as indicated at 20 in Fig. 1 of the drawing, the wing nuts 19 are loosened, and the members 11 and 12 are swung 80 outwardly on their hinged connections and the desired portion of the flag is unrolled from the roller portion within the holder, after which the sections 11 and 12 are again 85 moved toward each other and clamped in their closed position by means of the wing nuts 19. The stars 20, are arranged in the blue field 6 as disclosed in the Design Patent #52,411 granted September 10th, 1918 90 and they are intended to designate patriotic acts or services, as previously set forth so that when the owner of the flag performs services of a patriotic nature, additional to those indicated by the stars which are exhibited in the flag, a portion of the rolled portion of the flag is unrolled and exhibited which unrolled portion should carry the 95 number of stars corresponding to the additional number of patriotic acts or deeds performed.

Changes in details may be made without

departing from the spirit of this invention; but,

I claim:

1. A flag holder comprising a pair of sections arranged to receive a rolled portion of a flag therebetween, each section including an elongated flat body, inwardly extending hinge barrels formed on one longitudinal edge of each body, a hinge pin connecting the hinge barrels, a struck out tongue formed on one of the longitudinal edges intermediate the hinge barrels, inwardly extending right angularly disposed clamping jaws formed on the opposite longitudinal edges of the body and arranged to hold the bodies in spaced relation, outwardly extending clamping lugs formed on the transverse edges of the bodies, and means extending through the clamping lugs for holding the jaws together.

2. The combination with a flag including a rolled portion, of a holder for the flag including a pair of hinged sections arranged to receive the rolled portion of the flag, the sections having flat oppositely extending parallel bodies and gripping jaws formed on the bodies arranged to engage the flag and advance the roller portion thereof to prevent winding or unwinding of the flag and to hold the flat bodies in relation to each other, inwardly extending rows of hinged barrels formed on the longitudinal edges of the body opposite to the jaw, a hinge pin extending through the barrel, outwardly extending lugs formed on the transverse terminals of the body, the lugs having alined openings formed therein, bolts extending through said alined openings, and winged nuts fitted upon said bolts.

WILLIAM K. SPAULDING.
